UNITED STATES PATENT OFFICE

POMPEO CAPOCCI, OF HOLLANDALE, FLORIDA, ASSIGNOR OF ONE-HALF TO ANGELO CAMMARATA, OF HOLLYWOOD, FLORIDA

ORNAMENTAL LAMP SHADE

Application filed November 7, 1928, Serial No. 317,764. Renewed May 28, 1930.

My present invention has reference to an ornamental shade for electric lamps.

The primary object of the invention is the provision of a shade for this purpose which is of star shaped formation and in which the frame of the device is provided with a covering of translucent fabric or other translucent material of any desired color.

A further object is the provision of a frame for lamp shades that comprises outer and inner members, each stamped or shaped of cheap metal whose parts may be quickly associated to present a strong, efficient and ornamental structure.

15 A still further object is the provision of an ornamental shade for electric bulbs which may be employed as a Christmas ornament or a shade where soft lights are desired such as boudoirs, sleeping or sick rooms, etc.

20 The invention will be fully and comprehensively understood from a consideration of the following detailed description when read in connection with the accompanying drawings which form part of the application, with the 25 understanding, however, that the improvement is capable of extended application and is not confined to the exact showing of the drawings nor to the precise construction described and, therefore, such changes and 30 modifications may be made therefrom as do not affect the spirit of the invention nor exceed the scope thereof as expressed in the appended claims.

In the drawings:

35 Figure 1 is a side elevation of my improvement.

Figure 2 is an end view thereof.

Figure 3 is a substantially central longitudinal sectional view therethrough.

40 Figure 4 is a detail sectional view approximately on the line 4—4 of Figure 3.

Figure 5 is a similar section approximately on the line 5—5 of Figure 3.

45 Figure 6 is a perspective view of the bulb engaging spring clamp.

Figure 7 is a fragmentary elevation of one of the outer or side frames.

50 Figure 8 is a similar elevation of the inner frame.

Figure 9 is a plan view of the inner frame before the same is shaped.

Figure 10 is a detail perspective view to illustrate the manner in which the contacting portions or ends of the frame may be connected.

Figure 11 is an end or edge view of a slight modification.

Figure 12 is a fragmentary plan view of the frame employed in the construction disclosed by Figure 11.

Figure 13 is a plan view to illustrate the manner in which the bulb engaging clamp is supported.

Figure 14 is a side elevation thereof.

Figure 15 is a plan view of one of the spacer members.

Figure 16 is a perspective view of a modified form of spacer member.

Figure 17 is an elevation of a modification.

Figure 18 is a top plan view thereof.

In all of the structures disclosed by the drawings, the lamp shade has a configuration corresponding to that of a five pointed star.

75 In one of the embodiments of the improvement the outer or side frames each include a ring body 1 integrally formed at equidistantly spaced intervals with inwardly inclined extensions in the nature of V-shaped members 2. The V-shaped members, at the apex thereof, are formed with bendable ears 3, and the ring-shaped body portions 1, between the points of the star provided by the V-shaped members 2 are formed on their outer periphery with other bendable ears 4. 80 Each of the side or outer frames has its ring body provided with five V-shaped extensions 2.

85 The inner frame member, before the same is bent or shaped, is best illustrated by Figure 9 of the drawings. By reference to this figure it will be seen that the inner member comprises four diamond-shaped portions or sections 5, respectively, the said sections being connected by webs 6, and the outer sections are provided, at their apexes, with outwardly projecting tongues 7. Each of the V-shaped members is centrally formed with an integral brace plate 8, and the V-shaped members are provided with weakened lines 100

9 to permit of the outer portions thereof being bent to form the same with flanges 10. The flanged V-shaped elements are also bent upon themselves at their connections of the webs with the confronting ends or apexes thereof and likewise the tongues 7 are bent angularly.

The flanges 10 receive the outer edges of the points or V-shaped portions 2 of the outer or side members therein, and the ears 3 are bent over the webs 6 and the tongues 7 and are secured thereto by fastening means, such as clips 11 best illustrated by Figure 10 of the drawings. The ears 3 of the respective outer members or sides are bent over each other and likewise over certain of the webs of the inner frame member and are secured thereto by means of the clips 11.

If desired and as disclosed by the drawings, transverse plates 12 may be secured by means 13 to the upper and inner contacting portions of the frame members and the means 13 pass through oppositely rounded portions that provide eyes 14 at the corners of the connected spaced substantially U-shaped body portions 15 of the lamp bulb engaging clamp 16. By reference, especially to Figure 3 of the drawings it will be seen that an opening 17 is provided at the bottom of the frame so that a lamp bulb may be inserted through this opening and may be engaged by the springs arms of the clamp.

After the frame is assembled as above described, the same will present a structure representing a five pointed star, and the sides or faces, as well as the edges or ends of the frame are covered by a colored fabric sheet 18. The sheet does not extend through the opening 17. As disclosed by Figures 1 and 2 of the drawings, the shade is arranged over the bulb of a boudoir or other electric lamp body 19, but if desired, the upper point of the star-shaped shade may have attached thereto means for supporting the frame, so that the device may be employed as a Christmas ornament, the wire from the bulb in the shade, of course, passing through the opening 17.

In Figures 11 and 12 only two outer members or frame sides are employed, each of the said members including a ring body 20 from which extend equidistantly spaced points of V-shaped formation and which are indicated by the numeral 21. At their apexes the points are provided with apertures 22 and each of the ring bodies, between the points is provided with an aperture 23. The apexes of the points 21 are bent and there is passed through the openings 22 securing means 24. The openings 23 are designed to receive therethrough the bent parallel and outwardly extending arms 25 on the substantially U-shaped body portions 26 of the spring lamp bulb engaging clamps. The arms 25 also pass through openings in spacer plates 27 and

likewise pass through the bent ends 28 of the said plate. The ends of the arms are then bent against the frame and thereafter the sides of the frame are suitably covered as disclosed by Figure 11 of the drawings.

The spacer plates 27 are arranged adjacent to the top of the frame, while other spacer plates, such as disclosed by Figures 15 and 16 may be employed. In Figure 15 the spacer plate 29 has its ends formed with reduced and bendable extensions 30 to be passed through the openings 23 while in Figure 16 the spacer plate 31 has its ends bent, as at 32, to provide what may be termed ears and the same have openings therethrough to align with the openings 22 and suitable securing means, similar to that previously described are designed to pass through these openings.

In Figures 17 and 18 the construction is substantially similar to that disclosed by the first described form of the improvement, the exception being that the shade is designed to be horizontally arranged and that the fabric or like translucent covering for the frame does not cover the outer ring body 32 on the upper frame member, and to this ring body 32 there is fixed the ends of rounded spring clamps 33 that engage the lamp bulb 34 when the same is inserted through the open top of the improvement.

Instead of constructing the frame members of flat cheap metal as disclosed by the drawings the same can be formed of wire if desired.

Having described the invention, I claim:

1. A shade for electric bulbs, including the frame that comprises a pair of spaced ring members, each having on its outer periphery equidistantly spaced bendable substantially V-shaped extensions designed to have their ends brought into contact and to be secured together, spacer elements between the rings, a spring bulb clamp in the frame, and a translucent covering for the frame.

2. A shade for electric bulbs, including a frame, comprising a pair of spaced ring members having equidistantly spaced V-shaped projections thereon designed to be bent toward each other to have their apexes contact, means connecting said contacting points, spacer elements between the rings, a spring bulb engaging clamp supported on certain of the spacer elements, and a translucent cover for the frame.

3. A shade for electric bulbs, including a frame, comprising a pair of spaced ring members having bendable substantially V-shaped equidistantly spaced points designed to have their apexes brought together and connected, an inner member for the frame comprising a plurality of diamond-shaped elements whose edges are flanged and which are connected by webs and which have their upper ends formed with extending tongues, a transverse plate centrally connecting each of the diamond-

shaped members, said members designed to be bent upon themselves to have their flanges contacting with the outer edges of the V-shaped points on the ring members and to be secured to said points and to said ring members, said diamond-shaped members being one less in number than the V-shaped projections on the rings, spacer elements between the ring members of the frame and secured thereto, a spring bulb engaging clamp supported by certain of the spacer elements, and a translucent covering for the frame.

In testimony whereof I affix my signature.

POMPEO CAPOCCI.
